UNITED STATES PATENT OFFICE.

HARRY C. INNES, OF CINCINNATI, OHIO, ASSIGNEE TO THE PHILIP CAREY MANUFACTURING COMPANY, OF LOCKLAND, OHIO, A CORPORATION OF OHIO.

RAIL-FILLER.

1,171,441.

Specification of Letters Patent. Patented Feb. 15, 1916.

Application filed February 27, 1914. Serial No. 821,565.

To all whom it may concern:

Be it known that I, HARRY C. INNES, a citizen of the United States, and a resident of Cincinnati, in the county of Hamilton and State of Ohio, have invented certain new and useful Improvements in Rail-Fillers, of which the following is a specification.

My invention relates to railway track construction. Its object is to provide a filler for the rails of tracks laid in connection with paving, which may be conveniently installed and which will maintain the paving adjacent to the rail in proper condition without the necessity of frequent repairs.

My invention consists in the article of manufacture, and in the combination thereof with the railway rail and the paving elements or materials, as will be more fully described and claimed herein.

In the drawing: Figure 1 is a cross section of a track and part of the paving between and adjacent to the rails, illustrating the use of my invention with the girder-rail generally used in connection with paving; Fig. 2 is a plan view of part of a rail such as shown in Fig. 1 with some of the fillers associated therewith, the rail being curved, and this view serving to illustrate how fillers may be conformed to the rails under varying conditions; Fig. 3 is a perspective view of one of the fillers for the outside, and Fig. 4 is a perspective view of one of the fillers for the inside of the rail shown in Figs. 1 and 2; Fig. 5 is an enlarged section of one of the rails shown in Fig. 1 and the fillers associated therewith, showing the fibrous covering; Fig. 6 is a fragmentary section of one of the fillers with a modified covering; Fig. 7 is a section of a T-rail with the fillers and paving associated therewith, such rails being occasionally used in connection with paving; Fig. 8 is a cross section of a track and part of the paving between and adjacent to the rails, illustrating a modification of my invention in which part of the bed of the paving is extended in over the base of the rail against the web of the rail; Fig. 9 is a perspective view of one of the fillers used on the outside of the rail, and Fig. 10 is a perspective view of

one of the fillers used on the inside rail in this modification shown in Fig. 8.

The present practice in paving a street having railway tracks located therein, is to plaster the web of the rail with cement-mortar. This mortar shrinks from the rail in setting, and in time becomes loose and falls away from the rail unless supported, especially so if the tracks are being run over during construction, and if the mortar is made dry or is weak in cement. If paved with brick, the web is sometimes partially filled with a nose brick or a special block either of which is unsatisfactory, because of its inelasticity and non-adhesiveness to the rail, and liability to shift out of position relatively to the rail and permit the seepage of water to the foundation. When granite or wood blocks are used, it has been customary to plaster the webs of the rails with cement mortar; or, sometimes, the space adjacent the web between the ball and the base of the rail has been filled with pieces of ordinary lumber, bolted or otherwise held in place while filling in the adjacent portions of the street paving. These various methods involve the building up and fitting in of the filler to the required size and shape during the construction of the street, and involve extra work and time in building, as well as being unsatisfactory in use, because not possessing sufficient stability and resiliency to retain their proper relationship both to the rail and to the adjacent paving.

Planking absorbs moisture, which tends to expand it sufficiently to rupture or crack the adjacent paving material, and then, during the dry period, the contraction permits of a space or void, and a movement through which follows an abrasion of the wearing material; and alternate drying and wetting of the plank while not exposed to air causes it to rot and decay.

Cement mortar plastering does not repel water, but absorbs it, so that it is injurious to the rail by causing corrosion. Also, the cement plaster is easily acted upon by vibration of the track against the paving material, to the extent of dislodging and breaking down the plaster. Nose brick or blocks

used to fill the web space, being made of a certain shape and burned hard in that shape, do not fit the neat lines of the rail; and, as before stated, there is always a looseness, permitting seepage of moisture into the structure. Such hard material is chipped or broken in handling before put in place or through vibration after put in place.

I obviate all the above difficulties by using a bituminous substance or composition to fill the space along the web of the rail, and, by fitting snugly, to prevent seepage of moisture to the unexposed parts of the rail and protect the iron or steel against corrosion. It insures a complete filling of this space, and is, in the herein described forms, of great convenience during paving construction. It provides a vertical face against which the paving material joins, and if any vibration of the track takes place, the movement, being vertical does not injure the pavement. Since it has plastic, and cohesive qualities, the filler does not break or become brittle, and no material can be broken off and get under the paving surface to kick up the paving bricks or blocks, rendering the track and paving unsafe as well as unsanitary.

As shown in Figs. 1 to 5, inclusive, my improved filler, of plastic material, is preferably previously prepared and shaped, and provided in units 1 and 1' of given length, so associated with the rail 2 as to snugly fit the web 3, ball 4 and base 5 thereof, on the inside and outside of the track, respectively, and to occupy the entire space therebetween, and of such dimensions that said filler may be lightly driven to place therein. When so positioned, it will adhere thereto without any special or extraneous fastening, thereby permitting of the ready filling in and building up of the adjacent bed portion 6, cushion 7, usually of sand, and wearing surface material 8, of the pavement 9, or of any other construction of paving over the ties 10. Its use also affords a safeguard against any portion of the rail 2 not being closed in previous to laying the wearing surface material 8, and gives a neat substantially vertical surface 11 against which the wearing surface material 8 can be laid snugly, thereby reducing opportunities for large vertical joints or spaces for seepage of water. It also permits of the complete filling of said space before the adjacent pavement has been filled in, and permits of the entire surface whether of brick, wood block, granite, asphalt or other surfacing, to be laid closely to the ball 4 of the rail after my previously prepared filler 1 has been completely and permanently installed in position adjacent to the rail.

A more economical but less desirable construction is shown in Fig. 8, wherein the bed

6^a of the pavement, which bed is usually of concrete, is carried in over the base 5 of the rail 2 and terminates against the web 3, both on the inside and outside of the track, so that these terminal parts of the bed 6^a form part of the filling for the rail 2. My fillers 21 and 21' are then inserted on the inside and on the outside of the rail 2, respectively, filling the spaces above the bed 6^a and under the ball 4 of the rail 2, and fitting against the web 3 of said rail above the bed 6^a. The vertical surfaces 11 thus are shortened, and receive only the cushion 7 and wearing surface material 8 thereagainst. This construction will not protect the bed 6^a from the vibrations of the rails 2 as will the construction shown in Figs. 1 to 5, inclusive.

In either construction, the bed 6 or 6^a of concrete or other substantially non-elastic material will effectively resist extrusion of the elastic material of the filler down off the base of the rail, under heavy pressure from the upper pavement structure.

My improved fillers may be constructed of any suitable resilient or plastic material possessing waterproofing and insulating qualities, such as any of the bituminous compounds of sufficient dimension and density to retain its predetermined shape in handling and in use.

If desired, the side surfaces 12 and 13 may be coated with paper, cheesecloth, burlap, felt or other non-adhesive material 14, as indicated in Fig. 5, to prevent the fillers 1 from sticking together when being shipped, and also for the purpose of reinforcing and strengthening said filler. The article may be produced of asphaltic cement of a suitable degree of hardness or penetration to constitute the filler, or a combination of asphaltic cement of proper penetration and any other material inert in character, such as sawdust, or disintegrated wood, sand, pulverized stone, pulverized slag or pulverized cinders coated and cemented by the asphaltic cement, so proportioned as to give density, hardness, elasticity, and at the same time afford waterproofing and insulating properties.

If desired, the covering 14 may be omitted; or the filler may be given a coating of whitewash, talc, soap-stone, Portland cement or other non-adhesive material 15, as shown in Fig. 6. Such thin or light surfacing will prevent any running or sticking of adjacent fillers together in storage, boxing, shipping or handling; and when the filler is installed in the space, up against the rail, it will, when the adjacent paving has been placed in position against said filler, by reason of the surrounding pressure sufficiently adhere to and retain its proper position relative to the rail under various strains and stresses, and also under varying conditions of temperature that cause contraction and

expansion of the metals and other materials by which it is surrounded. Its use also serves as a deadener to sound, and it has the necessary insulating qualities for electric railway use. The filler 1 can be readily fitted to the rail and can be equally as well removed in the entire unit if desired, and re-used; and it is specially convenient and economical in handling and placing. It has such body and consistency that the finished product will not change its shape or form during changes of temperature, and is sufficiently homogeneous and tenacious not to become brittle. Furthermore, it is of such nature that it may be readily divided by cutting, and is sufficiently plastic to adapt itself to any irregularities in the rail or other surrounding material, thereby shaping itself to meet small changes in the line of the rails or other structural material.

A T-rail 16, such as shown in Fig. 8, is sometimes used for street car tracks, in connection with paving; and it is advantageous to have a suitable filler between the web of this rail and the adjacent paving, and my filler 1", of proper dimensions, may be applied to fit the web 17, ball 18 and base 19 of this rail 16 as shown. In any of the examples, the fillers may have the fibrous covering 14 as indicated in Fig. 5 or the coating 15 as shown in Fig. 6. Also in any instance, as with the inside of the girder-rail 2, where the shape is somewhat curved, as under the ball 4 of the rail, the filler 1 may be preformed with the concavity 20 therein, as in Fig. 4; or it may be made simply straight, and caused to conform snugly to the curve of the rail part, under pressure of insertion and by virtue of its plasticity. More pronounced irregularities, such as fish-plates or frogs, may require special cutting, which this material is highly adaptable for.

In all installations of my invention; and especially where a T-rail is used as shown in Fig. 7, requiring the formation of a groove on the inner side of the rail for the flanges to pass along; I prefer to confine the filler back of the vertical plane of the inner side 50 of the ball or head of the rail, and, with the T rail, to provide the groove entirely by cutting away the adjacent corner of the paving block 8. By thus having the filler confined entirely under the head of the rail, it is not exposed to disruptive influences in the flange groove, and at the same time it adequately supports the paving block 8 against extension under the ball or head of the rail. If the plastic material of the filler is exposed in this groove, fragments of rock or other hard substances, and even the dust of the road or street, will be ground into the plastic material, forcing some of the material up and out, and thus opening fissures in 65 the material itself and between it and the

rail parts, allowing the entrance of moisture or other foreign matter. (On the other hand, if the substantially non-elastic wearing-surface material, such as the paving block, is permitted to extend under the ball or head 70 of the rail, the constant vibration of the rail under traffic either breaks the paving block or dislodges it from its proper position in the paving.

It will be seen that with any of the above 75 constructions rapid deterioration of the paving along the rail is inevitable. My improvement not only by virtue of the plasticity and elasticity of the material of the filler, but by the novel disposition of this 80 material relative to the rail and the paving, eliminates the above difficulty.

The substantially vertical side of the filler where the paving material comes thereagainst is more or less adhesive to the non-elastic material of the paving. But even without any substantial adhesiveness, as with a covering as hereinbefore described, the plasticity of the material enables it to conform fully to the irregularities of the adjacent paving. This results in a very nearly perfect joint between the filler and the paving in the substantially vertical plane. At the same time, the elasticity permits of the slight relative movement of the filler and 90 pavement under the vibration of the rail without damage to the paving, such as raising or depressing the adjacent blocks; and where the paving is grouted, the grouting will not be broken between the adjacent 95 blocks and those more remote from the rail. This is the case with non-elastic filling material in the rail cavity, which, under the vibration, causes the adjacent blocks to act as levers, prying them loose from the more 100 remote blocks where grouted. If not grouted, this causes tilting the blocks or their deterioration by abrasion of the non-elastic 105 filling material with the non-elastic paving material.

While thus having the property of conforming closely to the irregularities of the paving material and allowing the slight movement without deterioration as above described, it will be understood that the elastic filling material readily renew its conformation to the irregularities after each disturbance. Thus, although a relative movement is permitted, there is also afforded a practically good joint to prevent 110 seepage of moisture.

The flange groove of paving along a track rail is always a receptacle for water drained from the paving surface; and even where the rail has the groove formed in it, as in Figs. 1 and 8, the joints of the paving with the rail are exposed to the water overflowing from this groove due to the passage of car wheels, or obstructions to the ready flow of the water along the groove. Thus, this part 125

of the pavement of a street is subjected to more exposure to moisture than any other part except the street gutters themselves; and in addition there is the necessity of 5 keeping up a proper relation between the paving and the repeatedly vibrated steel track rail in spite of the deteriorating influences of the moisture; whereas in every other part of the street, including the gutters, only like 10 materials are used; as for instance, grouted stone or brick or a uniform structure of cement, or asphalt against stone, brick or cement. Furthermore, in these other parts of the paving structure no relative movement is 15 required to be provided for except that due to contraction and expansion, which is exceedingly slow and gradual under even the most severe temperature changes, and in the direction of the general plane of the paving. 20 In the joint between the rails and paving these relative movements are abrupt and violent and at right angles to the general plane of the pavement.

For all relative movements caused by temperature changes, materials may be interposed to compensate for these without attrition of the parts; whereas in maintaining the proper relation of the paving to the track rails, the destructive influences are 30 far more complicated, as will be seen from the above. I find, however, that my improved rail filler as herein set forth, allows this relation to be maintained with a minimum of attention after installation.

35 Having fully described my invention, what I claim as new and desire to secure by Letters Patent is:

1. As an article of manufacture, a rail filler of material preformed to extend under the 40 ball of a rail against the web thereof and present a surface outward to paving material, and being of sufficient density to maintain its shape in handling but sufficiently plastic to adapt itself to any irregularities in the rail or other surrounding material.

2. As an article of manufacture, a rail filler of material preformed to extend under the ball of a rail against the web thereof and 50 present a surface outward to paving material, and being of sufficient density to maintain its shape in handling but sufficiently plastic to adapt itself to any irregularities in the rail or other surrounding material, and an outwardly non-adhesive outer coating or covering adhesively secured on said plastic material, and sufficiently yieldable to yield with said plastic material to said irregularities.

60 3. In combination, a track rail comprising a ball, a web and a base, and paving structure comprising substantially non-elastic material along the sides of said rail and with a concavity between said paving structure and web below the ball and above the base, a 65

filler of plastic elastic material supported in said cavity by said substantially non-elastic material.

4. In combination, a track rail comprising a ball, a web and a base, and a paving structure adjacent to said ball and base, and comprising substantially non-elastic material along the side of said base and with a concavity between said paving structure and web below the ball and above the base, a 70 filler of preformed plastic elastic material in said cavity and supported by said substantially non-elastic material against extrusion off of said base.

5. As an article of manufacture, a rail 80 filler of material preformed to extend under the ball of a rail against the web thereof and present a surface outward to substantially non-elastic paving material, of sufficient density to maintain its shape in handling 85 but sufficiently plastic to adapt itself to any irregularities in the rail or other surrounding material, and to be confined back of the vertical plane of the inner side of the ball of the rail, but to support said substantially 90 non-elastic material against extension under the ball of the rail.

6. In combination, a track rail comprising a ball, a web and a base, and paving structure comprising substantially non-elastic material along the side of said rail and with a concavity between said paving structure and web below the ball of the rail, a filler of plastic elastic material supported in said cavity by said substantially 95 non-elastic material, and confined back of the vertical plane of the inner side of the ball of the rail, but supporting said substantially non-elastic material against extension under the ball of the rail.

7. As an article of manufacture, a rail filler of adhesive elastic material preformed to extend under the ball of a rail against the web thereof and above the base thereof and present a surface outward to paving 100 material, and being of sufficient density to maintain its shape in handling but sufficiently plastic to adapt itself to any irregularities in the rail or other surrounding material, and outwardly non-adhesive outer 110 coatings or coverings adhesively secured on and confined to opposite substantially vertical sides of said adhesive material with said adhesive material exposed at its top and bottom, to adhere to said ball and base, respectively, of the rail.

8. In combination, a track rail comprising a ball, a web and a base, and paving structure adjacent to said ball and base, and comprising substantially non-elastic material 125 along the side of said base and with a concavity between said paving structure and web below the ball and above the base, a filler preformed of adhesive plastic elastic material in said cavity and supported by 130

said substantially non - elastic material against extrusion off of said base, and outwardly non-adhesive coatings or coverings adhesively secured on and confined to opposite substantially vertical sides of said adhesive material with said adhesive material exposed at its top and bottom, to ad-

here to said ball and base, respectively, of the rail.
